UNITED STATES PATENT OFFICE.

JOHN L. SOMMER, OF NEWARK, NEW JERSEY, ASSIGNOR TO J. L. SOMMER MANUFACTURING CO., A CORPORATION OF NEW JERSEY.

DESIGN FOR AN EYEGLASS SCREW-DRIVER.

46,703.

Specification for Design.

Patented Nov. 24, 1914.

Application filed August 12, 1914. Serial No. 856,500. Term of patent 14 years.

To all whom it may concern:

Be it known that I, JOHN L. SOMMER, a citizen of the United States, residing at Newark, in the county of Essex and State of New Jersey, have invented a new, original, and ornamental Design for an Eyeglass Screw-Driver, of which the following is a specification, reference being had to the accompanying drawing, forming part thereof.

Figure 1 is a side view of an eye glass

screw driver, showing my new design; Fig. 2 is an edge view of the same, and Fig. 3 is a cross sectional view on line A—A of Fig. 1.

I claim:

The ornamental design for an eye glass screw driver, as shown.

JOHN L. SOMMER.

Witnesses:

FLORENCE M. POHLIG,

CHARLES MUNTRICK.
